CONTAINER

Carroll H. Gullion, Chicago, and Charles P. Evans, Wilmette, Ill., said Gullion assignor to Swift and Company, Chicago, Ill., a corporation of Illinois

Application November 30, 1936, Serial No. 113,506

5 Claims. (Cl. 229—87)

This invention relates to an improved container.

One of the objects of the invention is to provide an improved container.

5 Another object of the invention is to provide a container having an improved outer wrapper.

Other objects of the invention will be apparent from the description and claims which follow.

10 The present invention contemplates the use of a fiber-board canister having recessed end closures. In accordance with the present invention, the container is provided with an outer wrapper of cellulosic or other transparent material, which wrapper is suitably cut to encase the outer wall of the container and provide end edges adapted for overlapping the ends of the container. The wrapper is held in place by false end members secured within the recessed end

20 closures.

Reference is had to the drawing in which like characters of reference are used to designate similar elements.

Figure 1 is a perspective view illustrating one form of container with which the wrapper of the present invention may be used.

Figure 2 is a perspective view of the container shown in Figure 1 illustrating the manner of applying the wrapper thereto.

30 Figure 3 is a top plan view of the container shown in Figure 2.

Figure 4 is a plan view of the false end member for securing the wrapper relative to the top end closure of the container.

35 Figure 5 is a bottom plan view of the container shown in Figure 2.

Figure 6 is a plan view of the false end member for securing the wrapper to the bottom end closure of the container.

40 Figure 7 is a fragmentary sectional view of the container shown in Figure 1 showing the manner of securing the false end members in the end closures thereof.

The container, illustrated in the drawing, comprises body 1, bottom end closure 2 and top end closure 3. End closure 2 comprises cupped disk 4 provided with peripheral flange 5. Disk 4 is inserted through body 1 and secured as by curling the end edge 6 of body 1 over and against flange 5, thus providing a recessed end closure having peripheral marginal flange 7.

45 Top end closure 3 comprises cupped disk 8 provided with peripheral flange 9 and cover securing ring 10. The end edge 11 of ring 10 is curled over and against flange 9, thus provid-

ing a recessed top end closure having peripheral marginal flange 12.

If desired, end edge 13 of body 1, as shown in Figure 7, may be curled over and against the outer wall of body 1, thus providing a reenforced outer edge 14. The container is closed by fitting ring 10 over lapped edge 14.

5 It will be understood that the specific construction of the container is not a particular part of the invention but that the form of construction shown has been chosen merely as a preferred illustration of a fibrous container to which the novel wrapper may be applied.

In accordance with the present invention, the closed, filled container, illustrated in Figure 1, 15 is provided with an outer wrapper 15 secured in the manner shown in Figures 2 and 7.

20 Wrappers 15 comprise substantially rectangular sheets of cellulosic or other transparent material. In practice, wrapper 15 is suitably cut so that when placed around the outer wall of body 1, it will overlap at its longitudinal edges 16 and in addition, will provide end edges 17 and 18 adapted for folding over and against end closures 2 and 3, respectively. If desired, overlapped edges 16 may be secured by a suitable sealing adhesive or folded to provide a seamed joint.

25 End edge 17 is rigidly secured relative to end closure 2 by disk 19, of cardboard or other suitable material, cut to provide a pressed fit between the inner walls of marginal flange 7. Disk 19 is placed over the folded edges 17 and 20 and pressed within marginal flange 7. End 18 is rigidly secured relative to end closure 3 by disk 20 cut to provide a pressed fit between the inner walls of marginal flange 12.

30 It will be seen that the frictional engagement of disks 19 and 20 against the end edges of wrapper 15, while being pressed within recessed end closures 2 and 3, will tightly and smoothly draw the wrapper relative to the outer wall of body 1, thus providing increased visibility of any printing indicia it may be desired to place on the outer wall of the container. It will also be seen that disks 19 and 20 are without an outer covering, thus providing additional advertising space and also end members suitably adapted for stacking the containers one above the other.

35 It will further be seen that the wrapper of the present invention serves to seal the cover closure relative to the body and that since the container cannot be opened without tearing or destroying the end disks, delivery of a fresh un-

adulterated product to the ultimate consumer is assured.

I claim:

1. In a container including a body wall having a recessed end closure, an outer wrapper encasing the body wall provided with an end edge foldable over and against the recessed end closure and means pressable circumferentially of the inner wall of the recessed end closure for frictionally securing the folded end edge of the wrapper against the inner wall of the recessed end closure.
2. In a fibrous container including a body wall having recessed end closures, an outer wrapper 10 encasing the body wall provided with end edges foldable over and against the end closures and means including fibrous disks pressable within the end closures and circumferentially of the inner walls of the end closures for frictionally 15 securing each of the end edges of the wrapper against the inner wall of its respective end closure.
3. In a container including a body wall and an end closure providing a peripheral marginal flange, a wrapper encasing the body wall and having an end edge foldable over and against the marginal flange and means pressable cir- 20 25

cumferentially of the inner wall of the marginal flange for frictionally securing the end edge of the wrapper against the inner wall of the marginal flange.

4. In a container including a body wall and an end closure providing a peripheral marginal flange, an outer wrapper encasing the body wall provided with an end edge foldable over and against the inner wall of the marginal flange and means including a disk pressable within and circumferentially of the inner wall of the marginal flange for frictionally securing the end edge of the wrapper against the inner wall of the marginal flange. 5 10

5. In a container including a body wall and an end closure providing a peripheral marginal flange, an outer wrapper encasing the body wall provided with an end edge foldable over and against the marginal flange and means including a false end closure pressable within and circumferentially of the inner wall of the marginal flange for frictionally securing the end edge of the wrapper against the inner wall of the marginal flange. 15 20

CARROLL H. GULLION. 25
CHARLES P. EVANS.
